COLOSTOMY GIRDLE AND SUPPORT

Florence M. Olver, Youngstown, Ohio

Application September 16, 1935, Serial No. 40,711

5 Claims. (Cl. 128—283)

This invention relates to a colostomy girdle and support.

The principal object of this girdle is to provide means for holding dressings in place over an abdominal colostomy.

5 A further object of this girdle is to provide means for holding detachable shields in place over the dressings.

A further object is to provide a detachable 10 crotch strap for rectal dressings which is formed to fit loosely and comfortably.

A further object is to provide a girdle supporting shields and dressings which will relieve the wearer of embarrassment due to the prominence 15 of the left side of the abdomen due to a colostomy.

A further object is to provide shoulder and leg 20 straps for holding the girdle in place so that it will not twist or move the dressings out of place.

A further object is to provide a covering for 25 the leg straps which may be quickly and easily removed and changed.

A further object is to provide a garment that is thin and cool but firm and comfortable and without staves, and simple to launder.

30 With the foregoing and other objects in view which will appear as the description proceeds, the invention resides in the combination and arrangement of parts and in the details of construction hereinafter described and claimed, it being understood that changes in the precise embodiment of the invention herein disclosed, can be made within the scope of what is claimed, without departing from the spirit of the invention.

35 The invention is illustrated in the accompanying drawing, wherein:—

Figure 1 is a front view of the girdle in position upon a form to show the manner in which it is worn.

40 Figure 2 is an inside view of the girdle showing the detachable shields.

Figure 3 is an enlarged detail perspective view showing a detachable leg strap and a removable covering for the same.

45 It is sometimes necessary that surgical operations be performed removing the lower end of the large intestine and closing the rectal opening. The end of the lower bowel remaining after the operation is then brought through an opening made in the left side of the abdominal wall and healed to the outer circumference of this opening, thereby providing an outlet for the waste material of the body which ordinarily would find an outlet through the rectum. After 50 an operation of this kind it is essential that

means be provided for holding dressings for the rectal operation. It is also necessary that means be provided for supporting dressings and shields covering the abdominal colostomy. This girdle is designed to provide comfort for the wearer as well as to provide a positive means for holding the necessary dressings in the proper places.

5 By referring to the drawing it will be seen that the girdle comprises a front panel 1, a back panel 2, back side panels 3, and front side panels 4. 10 When the garment is being placed in position for wearing shoulder straps 5 and 6 are placed over the shoulders. It will be seen that the back portions of the straps 5 and 6 are held in spaced relation to each other by means of a connecting 15 strap 7. It will also be seen that the lower end 8 of the strap 6 is secured to the left side panel 4 directly above a fastening edge 9 so that the left side of the garment will be held in a position for easy fastening when the dressings are in place. 20 It will also be seen that the front panel 1 is provided with a fastening strip 10, and while the drawing shows the fastening edges secured by means of buttons, any desirable fasteners, such as hooks and eyes, snaps, etc., may be used. 25

By referring to the drawing it will be seen that the front panel 1 is provided with a detachable shield 11. It will be seen that there is also provided a detachable dressing shield 12 which is secured at its bottom edge 13 to the girdle. It 30 will be seen that the bottom edge 13 of the dressing shield 12 extends below a lower curved edge 14 of the front panel 1 in order to prevent soiling of the panel 1.

In order to prevent the girdle from slipping 35 upwardly there is provided leg straps 15 which are protected by means of detachable coverings 16, which are left free at the back. By referring to Figure 3 it will be seen that the detachable covering 16 is provided with a closed end having 40 a relatively small opening 17 for the reception of a hook 18 on the leg strap 15. The leg straps 15 are preferably made of elastic and the covering 16 prevents their becoming soiled. These leg straps are attached in any suitable manner to 45 the front panel 1 and at the seams between the back and front side panels 3 and 4.

It will also be seen that there is provided a crotch strap 19 which is secured at one end to the edge 14 of the front panel 1 and at the other 50 end to an extended member 20 on the back panel 2. This crotch strap 19 is for the purpose of holding rectal dressings and may be detached when it is no longer necessary to be worn.

By referring to Figure 2 it will be seen that 55

the lower edge of the back panel 2 and the back side panels 3 has a pronounced curve 21 which removes all pressure from the buttocks which would cause distress at rectum.

5 By referring to the drawing it will be seen that the girdle is provided with fastening means 22 for garters. On a man's garment these would be dispensed with.

What I claim is:—

- 10 1. A colostomy girdle formed with a front and back panel and back and front side panels, fastening means for said girdle, shoulder straps secured to said girdle, leg straps attached to said girdle in order to hold said girdle firm against body and to prevent slipping, a shield secured to said front panel, and a dressing shield secured to lower edge of said front panel for holding dressings in place, said dressing shield extending below the curved lower edge of said front panel
- 15 20 2. A colostomy girdle formed with a front and back panel and front and back side panels, fastening means for said girdle, shoulder straps secured to said girdle, leg straps attached to said girdle in order to hold said girdle firm against body and to prevent slipping, said back panel and back side panels having their lower edges formed with a pronounced curve to remove pressure from buttocks, a shield secured to said front panel, a dressing shield secured to lower edge of said front panel for holding dressings in place, said dressing shield extending below the curved lower edge of said front panel to prevent soiling of said girdle.
- 25 30 35 3. A colostomy girdle formed with a front and back panel and front and back side panels, fastening means for said girdle, shoulder straps secured to said girdle, leg straps attached to said girdle in order to hold said girdle firm against body and to prevent slipping, said back panel and back side panels having their lower edges formed with a pronounced curve to remove pressure from buttocks, a shield secured to said front

panel, a dressing shield secured to lower edge of said front panel for holding dressings in place, said dressing shield extending below the curved lower edge of said front panel to prevent soiling of said girdle, means for fastening garters to 5 said girdle.

4. A colostomy girdle formed with a front and back panel and front and back side panels, fastening means for said girdle, shoulder straps secured to said girdle, detachable leg straps for said girdle in order to hold said girdle firm against body and to prevent slipping, detachable coverings protecting said leg straps, said coverings having a small opening in one end for the reception of a fastener on said detachable leg straps, 10 a shield secured to said front panel, a dressing shield secured to lower edge of said front panel for holding dressings in place, said dressing shield extending below the curved lower edge of said front panel to prevent soiling of said girdle, an 15 extended member on said back panel, a crotch strap attached to said front panel and to said extended member on back panel for the purpose of holding rectal dressings in place, means for fastening garters to said girdle. 20

5. A colostomy girdle formed with a front and back panel and front and back side panels, fastening strips on said front panel and left front side panel, shoulder straps secured to said girdle, a connecting strap between back portions of 30 said shoulder straps to prevent straps from slipping off shoulders, said left shoulder strap secured directly above fastening strip on said front side panel in order to hold the left side of the girdle in position for fastening, detachable leg 35 straps for said girdle for holding said girdle firm against body and to prevent slipping, detachable coverings protecting said leg straps, a shield secured to said front panel, a dressing shield secured to lower edge of said front panel for holding dressings in place, an extended member on 40 said back panel, a detachable crotch strap attached to said front panel and to said extended member on back panel for the purpose of holding rectal dressings in place, means for fastening 45 garters to said girdle.

FLORENCE M. OLVER.
